UNITED STATES PATENT OFFICE

173,140

AUTOMOBILE

Herbert A. Blenkle, Leonia, N. J., assignor to Marco Mfg. Company, Wheatland, Pa., a corporation of Delaware

Application February 15, 1954, Serial No. 29,011

Term of patent 14 years

(Cl. D14—3)

To all whom it may concern:

Be it known that I, Herbert A. Blenkle, a citizen of the United States, residing at Leonia, in the county of Bergen and State of New Jersey, have invented a new, original, and ornamental Design for an Automobile, of which the following is a specification, reference being had to the accompanying drawing, forming a part thereof.

Fig. 1 is a perspective view showing the front and one side of an automobile embodying my new design; and

Fig. 2 is a rear view thereof.

The side opposite that disclosed in Fig. 1 is substantially similar to the one shown.

I claim:

The ornamental design for an automobile, as shown and described.
